LIGHTING SYSTEM

Lindsley Schepmoes, New Haven, Conn., assignor
to The Safety Car Heating & Lighting Com-
pany, a corporation of New Jersey

Application April 2, 1935, Serial No. 14,268

8 Claims. (CL 248—7.35)

This invention relates to lighting apparatus particularly adapted to illuminate a railroad car or the like.

One of the objects of this invention is to provide lighting apparatus which is simple in construction, thoroughly efficient and reliable in operation. Another object of the invention is to provide apparatus of the above nature which is light and inexpensive in construction yet pleasing in appearance and particularly well adapted for use in railroad cars or the like. Another object is to provide an apparatus of the above nature which can be readily installed in cars of standard construction without necessitating material alterations for the interior of the car. Another object is to provide apparatus of the above nature which illuminates the interior of the car with an even intensity in the lower portions of a car or the like occupied by passengers. Another object is to provide apparatus of the above nature which can be rapidly installed or replaced. Another object is to provide apparatus of the above nature which precludes the necessity of wiring the car. Another object is to provide apparatus of the above nature which may be suitably installed in a car provided with an air conditioning system. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

35 In the accompanying drawings in which are shown several of the various possible embodiments of this invention.

Figure 1 is a diagrammatical cross section of the upper portion of a railroad car or the like;

40 Figure 2 is a fragmentary sectional perspective view of one embodiment of my invention;

Figure 3 is a fragmentary perspective view of another embodiment of my invention; and

45 Figure 4 is a fragmentary sectional perspective view of another embodiment of my invention.

Similar reference characters refer to similar parts throughout the several views of the drawings.

50 As conducive to a clearer understanding of certain features of this invention, it should be noted that, in many of the lighting systems now in use, illumination of the car or the like is achieved by individual groups or clusters of lights or electric light bulbs spaced along the ceiling of

a car. In many instances, the individual groups are both cumbersome and heavy and give rise to bothersome glare with resulting annoyance to the passengers. In air conditioned cars, for example, in which air ducts are disposed along the ceiling or in the clerestory of the car, these individual groups or clusters of lights are generally located along the center of the car between the ducts which, in many cases, results in a partial shading of the light emanating from the clerestory, and in others, results in an undue multiplication of individual clusters in order to provide sufficient illumination. This in turn results in added expense and trouble in wiring the car and in providing numerous individual fixtures. As the modern tendency in car construction is to reduce the total weight of the car as much as possible, multiplication of lighting fixtures adds to the total weight of the car. Furthermore, the individual group or cluster is not in keeping with modern streamline design and, therefore, does not harmonize with the general appearance of the interior of the car. One of the objects of this invention is to produce a system of lighting a railroad car or the like which overcomes the above-mentioned difficulties as well as many others.

Referring first to Figure 1, there is shown a railroad car generally indicated at 10 having the usual clerestory 11 and side walls 12 and 13. Side walls 12 and 13 curve inwardly to form roof portions 14 and 15, these portions 14 and 15 constituting part of the ceiling of the car and connecting with the side walls of clerestory 11. Clerestory 11 includes ceiling portions 16 and 17 which form a false roof beneath roof 11a thereof thus to form enclosures 18 and 19 which may be utilized as air ducts when an air conditioning plant or the like is installed in the car. Between ducts 18 and 19, I preferably dispose my lighting apparatus generally indicated at 20.

As is more clearly shown in Figure 2, lighting apparatus 20 comprises an elongated illuminator 21 which extends substantially throughout the length of the car and is preferably built up of individual sections. The details of construction of illuminators suitable for this purpose, as well as mounting apparatus, are described in my pending application, Serial Number 14,266. Illuminator 21 is secured in any suitable manner to a conduit 22 in which are located electric conductors 23 connected by suitable socket members or the like (not shown) to the filament in illuminator 21. Conduit 22 is suitably secured in an inverted channel member 24 preferably by way

of screws or the like so that it may be removed to gain access to conductors 23. Channel member 24 is secured to a pair of curved plates 25 and 26 which in turn are attached to clerestory roof 11a in any desired manner. Suitably secured to channel member 24 and depending downwardly therefrom is a pair of reflecting members 27 and 28 located on opposite sides of illuminator 21 and having their bottom edges preferably in the vicinity of ceiling portions 16 and 17. A plurality of plate-like reflecting members 29 are preferably equidistantly spaced along illuminator 21 and are connected to reflecting members 27 and 28 in any suitable manner. These plate-like members are preferably opaque and are provided with suitable indentures 29a so that they may extend about the illuminator.

Thus, reflector members 27 and 28 together with plates 29 form a unit, preferably divided into longitudinal sections along the length of the car. These units are preferably held in position so that the upper edges 27a and 28a rest against the respective bottom edges of the sides of channel member 24. Thus, I prefer to provide a plurality of spring clips 15 pivotally secured to conduit 22 by rivets or the like 16. These clips are shaped so that the extremities thereof rest against reflector members 27 and 28 to hold the sections in the above-described position. By turning the spring clips, the individual sections may be removed to gain access to the illuminator as well as conduit 22.

Curved plates 25 and 26 are preferably substantially spaced from reflecting members 27 and 28, and with ceiling portions 16 and 17, form respectively the bottoms and inner side walls of air ducts 18 and 19. A number of air inlet ports 30 are suitably formed in plates 25 and 26 to permit the flow of air from ducts 18 and 19 into the car. It may now be seen that, as lighting fixture 20 extends substantially throughout the length of the car in a channel formed by air ducts 18 and 19, they direct light of even intensity downwardly throughout the length of the car. Furthermore, reflecting members 27 and 28 reflect light from the illuminator downwardly while reflecting plates 29 prevent substantial horizontal diffusion of light. In this manner passengers in the car receive an adequate supply of light for reading purposes or the like and yet, if they chance to glance upwardly, they do not look directly on the illuminator.

In Figure 3 in which is shown another embodiment of this invention, the air ducts are formed by ceiling portions 16 and 17 which, in this instance, extend to and preferably connect with reflecting members 27 and 28; the interior walls of the ducts comprise plate members 31 and 32. Channel member 24 of lighting fixture 20 is located between ducts 18 and 19 and is preferably secured directly to clerestory roof 11a. Plate member 31 is provided with flanges 31a and 31b which are respectively secured as by spot welding, for example, to clerestory roof 11a and ceiling portion 16 while flanges 32a and 32b of plate member 32 are respectively secured in a like manner to clerestory roof 11a and ceiling portion 17. Flanges 31b and 32b may also be secured to reflecting members 27 and 28 respectively and, under certain conditions, this has been found more desirable.

A suitable number of air inlet ports 33 are provided in ceiling portions 16 and 17 through which air may flow from ducts 18 and 19 into the car. Ports 33 are preferably equidistantly

spaced from one another and the ports preferably are positioned between the plate members 29. Thus, as ports 33 are substantially adjacent the edges of reflecting members 27 and 28, they form with plates 29 a design of pleasing appearance in the ceiling of the car which is in harmony with an interior characterized by length rather than breadth. It will further be seen that a large number of ports 33 may be formed in ducts 18 and 19 fully capable of furnishing an adequate supply of air to the car.

Referring now to Figure 4 in which is shown another embodiment of my invention, channel member 24 of illuminating fixture 20 is preferably secured directly to clerestory roof 11a and is disposed between air ducts 18 and 19. Air ducts 18 and 19 are formed by ceiling portions 16 and 17 and interior wall portions generally indicated at 34 and 35. As walls 34 and 35 are substantially similar in construction, wall 34 only will be described in detail. Thus, wall 34 comprises a plate 36 which has an upper flange 36a secured as by spot welding, for example, to clerestory roof 11a. The lower flange 36b of plate 36 has secured thereto, as by screws 37, a curved plate 38; this curved plate extends inwardly and downwardly and is preferably connected to reflecting member 27. A suitable number of hangers 39 are secured to plate 36 desirably by rivets 40 and extend therebelow. Hangers 39 have right angle portions 39a secured to ceiling portion 16. As ceiling portion 16 is thus spaced below the upper edge of plate 38 a continuous inlet port 41 is provided which permits the flow of air from duct 18 into the car. Air enters 35 from the duct in a lateral direction and is deflected downwardly by plate 38. Similarly, wall 35 includes a plate 42 and a curved plate 43 which, with ceiling portion 17, forms inlet port 44 for duct 19. It will now be seen that in this embodiment I have provided lighting apparatus combined with the air ducts which is particularly well adapted for use in modern railroad cars or the like. Furthermore, the elongated inlet ports 41 and 44 permit a maximum influx of air into the car from the ducts and also distribute the air evenly throughout the length of the car.

Referring now to Figure 1, it may be seen that reflecting members 27 and 28 preferably have their lower edges substantially in the plane of the uppermost surfaces of ceiling portions 16 and 17. Accordingly, light rays emanating from illuminator 21 are diffused throughout the lower portions of the car, and no shadows are cast by air ducts 18 and 19 in the area in which illumination is desired. The area of illumination, as indicated by the dotted lines in Figure 1, is sufficiently ample to provide light of even intensity at the reading plane or the top of a dining table as the case may be.

By referring to Figures 2, 3, or 4, it may be noted that reflecting members 27 and 28 direct light rays emanating from illuminator 21 in vertical and lateral directions with respect to the illuminator, and plates 29 substantially prevent reflection of light rays in longitudinal directions with respect to the illuminator. Thus, unless the passenger looks directly into the illuminator, he is not subjected to any glare and accordingly is not troubled by any overintensity of light while sitting or standing in a normal position.

It will further appear that air ducts 18 and 19 in any of the embodiments of my invention may be readily installed in any car, or the like,

of standard construction with a minimum amount of trouble and expense and that the lighting fixture 20 may likewise be installed without extensive wiring or material alteration of the car 5 interior. Furthermore, the entire apparatus is well able to withstand long usage and constant vibration without troublesome rattling or other undesirable results.

It will thus be seen that I have provided an 10 apparatus which is thoroughly practical, efficient, and durable and in which the several objects hereinabove mentioned, as well as many others, are successfully accomplished.

As many possible embodiments may be made 15 of the above invention and as many changes might be made in the embodiments above set forth, it is to be understood that all matter hereinbefore set forth, or shown in the accompanying drawings, is to be interpreted as illustrative 20 and not in a limiting sense.

I claim:

1. In lighting apparatus for railroad cars or the like, in combination, a car including a clerestory and a pair of air ducts disposed on opposite 25 sides of said clerestory and extending longitudinally of the car, an elongated illuminator secured to the ceiling of said clerestory between said ducts and reflecting means secured to said ceiling forming side walls for said ducts reflecting 30 light rays emanating from said illuminator.

2. In lighting apparatus for railroad cars or the like, in combination, a car including a clerestory and a pair of air ducts disposed on opposite sides of said clerestory and extending longitudinally of the car, an illuminator disposed 35 between said ducts and suspended from the ceiling of said car, a pair of reflecting members secured to the ceiling of said car on opposite sides of said illuminator and forming side walls for 40 said air ducts, and means forming inlet ports in said ducts whereby air may flow therefrom into said car.

3. In lighting apparatus for railroad cars or the like, in combination, a car including a clerestory and a pair of air ducts disposed on opposite 45 sides of said clerestory and extending longitudinally of the car, said ducts forming a channel extending along the central portion of the car, an illuminator disposed between said ducts and secured to the ceiling of said car and substantially coextensive with said car, a pair of reflecting members secured to the ceiling of said car on opposite sides of said illuminator and depending therefrom to substantially the plane 55 of the bottom of said air ducts, means forming inlet ports in said ducts, and a plurality of plate-like members vertically related to the longitudinal axis of said illuminator.

4. In lighting apparatus for railroad cars or the like, in combination, a car having a clerestory, a pair of plate-like portions extending from the sides of said clerestory and spaced beneath the top of said clerestory to form a longitudinal opening along the central portion of said 60 clerestory, a pair of U-shaped side portions secured to said plate portions and secured to the top of said clerestory, said side portions and said plate portions together forming a pair of longitudinal air ducts along the opposite sides of said clerestory, reflecting means disposed between said side portions adjacent said longitudinal opening, illuminating means suspended beneath said reflecting means, and a plurality of plate-like 65

parts secured to said reflecting means and occupying planes substantially at right angles to said side portions.

5. In lighting apparatus for railroad cars or the like, in combination, a car having a clerestory, 5 plate portions extending inwardly from the sides of said clerestory and spaced beneath the top of said clerestory, said plate portions terminating short of the center line of said clerestory to form a longitudinal opening into said clerestory, a pair 10 of side portions connected to the top of said clerestory substantially adjacent the inner longitudinal edges of said plate portions and terminating above said plate portions to form air ducts along the sides of said clerestory having longitudinal slot-like openings adjacent said first-mentioned longitudinal opening, a plurality of bracket members secured to said side portions and said plate portions, a pair of deflecting portions 15 secured to the bottoms of said plate portions 20 and thence curving downwardly to points spaced inwardly from the inner longitudinal edges of said plate portions, channel-like reflecting means connected to said deflecting portions and extending upwardly between said side portions, illuminating means disposed beneath said reflecting means, and a plurality of plate-like reflector members disposed within said reflecting means substantially at right angles to said side portions.

6. In lighting apparatus for railroad cars or the like, in combination, a car having a clerestory, a pair of plate-like portions extending from the sides of said clerestory and spaced beneath the top of said clerestory to form a longitudinal opening along the central portion of said clerestory, 30 a pair of U-shaped side portions secured to said plate portions and secured to the top of said clerestory, said side portions and said plate portions together forming a pair of longitudinal air ducts along the opposite sides of said clerestory, 35 reflecting means disposed between said side portions adjacent said longitudinal opening, and illuminating means suspended beneath said reflecting means.

7. Lighting apparatus for railroad cars or the like comprising, in combination, a car, means forming a supporting member extending longitudinally of said car, means forming an elongated reflecting member extending longitudinally of said car, an elongated light source connected to 45 one of said members, and a plurality of fastening elements movably secured to one of said members and movable into a position to fasten together in related assembly both of said members, said fastening elements being movable into another position 50 to permit separation of said members from their assembled relationship.

8. In a lighting system for a railroad car or the like, in combination, a car, means forming a pair 55 of air ducts along the upper portion of said car, means forming a wire conduit between said air ducts, an elongated illuminator operatively related to said conduit, an elongated reflector, a plurality of plate members secured to said reflector in spaced parallel planes transverse to the longitudinal axis of the reflector, and means 60 pivotally associated with said conduit and pivotable into a position to engage said reflector to mount the reflector and said plate members as a unit in operative relation to said illuminator, 65 whereby the unit may be easily attached to and detached from the conduit without disturbing the illuminator.

LINDSLEY SCHEPMOES.
